(57) **CLAIM**

The ornamental design for a ratchet ring as shown and described.

DESCRIPTION

FIG. 1 is a top, front, and right perspective view of a ratchet ring showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view taken along the line 8-8 in FIG. 2; and,

FIG. 9 is a perspective view showing the ratchet ring in use. The broken lines in the drawings illustrate portions of the ratchet ring which form no part of the claimed design. The dot-dashed lines shown in FIG. 9 illustrate an o-ring and form no part of the claimed design.
